(57) **CLAIM**

The ornamental design for a brush, as shown and described.

DESCRIPTION

FIG. 1 is a top plan view of a brush showing our new design; FIG. 2 is a side elevational view thereof;

FIG. 3 is a bottom plan view thereof;

FIG. 4 is an elevational view of the side opposite that shown in FIG. 2;

FIG. 5 is a right end elevational view thereof; and,

FIG. 6 is a left end elevational view thereof.

The bristles are partially shown in FIGS. 2 and 4 for ease of illustration.
